UNITED STATES PATENT OFFICE.

BERNARD STEMBER, OF NEW YORK, N. Y.

DESIGN FOR A BAG FASTENER.

Application filed February 14, 1928. Serial No. 25,441. Term of patent 3½ years.

To all whom it may concern:

Be it known that I, BERNARD STEMBER, a citizen of the United States, residing at New York, county and State of New York, have invented a new, original, and ornamental Design for a Bag Fastener, of which the following is a specification, reference being made to the accompanying drawing, forming a part thereof.

The figure is a perspective view of a bag fastener having the new and ornamental design applied thereto.

I claim:

The ornamental design for a bag fastener as shown.

BERNARD STEMBER.
